UNITED STATES PATENT OFFICE.

HENRY A. FINK, OF SYRACUSE, NEW YORK, ASSIGNOR TO CONTINENTAL CAN COMPANY, INC., OF NEW YORK, N. Y., A CORPORATION OF NEW YORK.

METHOD OF FLANGING CAN BODIES AND FLANGING HEAD FOR CARRYING OUT THE SAME.

Application filed March 26, 1925. Serial No. 18,428.

The invention relates to new and useful improvements in flanging heads for turning flanges on a can body, and to the method of shaping the flanges on said body.

5 An object of the invention is to provide a flanging head with a die adapted to enter the can body and simultaneously turn a flange on the end thereof throughout the entire extent of the body, which flanging head is also 10 provided with means for limiting the extent to which the flange is turned, and means for engaging both sides of the turned flange for shaping the same into a predetermined form.

A further object of the invention is to provide 15 a flanging head of the above type with a sectional limiting and bumping ring, which may be opened so as to permit the flange after it is formed being withdrawn from the flanging head.

20 A still further object of the invention is to provide a method of forming a flange on the can body, wherein the entire end of the can body is turned outwardly to a limited extent to form a flange and wherein both sides of the 25 flange are positively shaped so as to form a predetermined flange and also to form flanges which are uniform in shape and size.

These and other objects will in part be obvious and will in part be hereinafter more 30 fully disclosed.

In the drawings which show by way of illustration one embodiment of the invention—

Figure 1 is a sectional view through the 35 center of a machine showing two of the flanging heads, one of which is about to enter the can body for flanging the end thereof, and the other as having turned and formed its flange.

40 Fig. 2 is a view showing more or less diagrammatically the arrangement of the flanging head in a continuous rotating machine, and also the manner of moving the sectional portions of the head relative to the can body, 45 and

Fig. 3 is an enlarged detail showing the final shaping of the flange.

The invention is preferably embodied in a machine of the general type of that granted 50 August 8, 1916, to L. C. Krummel, No. 1,194,038, except that the flanging head of the present invention forms and completes the flange in one operation, and therefore, there is only one rotating turret carrying the flang-

ing heads. It is not thought necessary to describe the entire machine, and applicant has merely shown and described the new features on the flanging head. 55

In making can bodies, particularly those known to the trade as an open top can, the cylindrical body portion is first made, after which each end is provided with a small flange extending at substantial right angles to the cylindrical wall of the body portion. The bottom portion of the can is secured to the can body by a double seam formed by rolling a flange on the can body into a seam with the metal of the can end therefor. The other can end is secured to the body portion in a similar manner, after the can is filled. These 60 double seams have to be made very accurately in order to form a tight joint so that the can when closed will not leak. It is also 65 desirable that these flanges shall be as small as possible, and the can ends secured to the body portions as small in diameter as possible, so that a minimum amount of metal may be used in the making of the can. Billions of cans of the type referred to are made each 70 season, and any little saving in the metal when multiplied by such numbers, amounts 75 to a great deal. It has been found in practice that many of the leaks in cans are caused by imperfectly formed seams which have been 80 due to the improper formation of the flange on the body of the can. One reason why the flanges have been improperly formed has been due to the fact that the metal varies in 85 hardness, and sometimes in thickness, and therefore, it cannot be relied upon to shape 90 itself into a proper flange merely by a die applied internally of the can body.

The present invention is directed to a method of flanging the can end, wherein the flange is positively controlled throughout the entire 95 formation thereof, so that the flange may be turned at substantial right angles to the outer face of the body of the can, and to a predetermined extent, thus forming flanges of uniform dimensions at all times. This has been accomplished by a flanging head which 100 has a turning die adapted to enter the open end of the can body, and engage the end thereof for rolling the metal outwardly into a flange, and by providing a limiting ring or 105 wall which will stop the outward movement of the metal when the flange is of proper width, and in addition to this, providing a

sectional bumping ring which is adapted to engage the one face of the flange while the other face of the flange is engaged by the head carrying the die, and thus the flange is 5 properly shaped.

The method and apparatus will possibly be better understood by a brief reference to the drawings, which illustrate the novel features of a flanging head for carrying out the 10 method. The machine includes a central shaft 1 which extends from one side of the machine to the other. Mounted on and carried by this rotating shaft are four flanging heads at each side of the machine, making 15 in all eight flanging heads. These flanging heads operate in pairs so as to form a flange at both ends of the can body at the same time. This is the general arrangement of the structure of the turrets shown in the Krummel 20 patent above referred to. Mounted on the shaft 1 and turning therewith is a support 2 which carries all the flanging heads at one side of the machine, and a similar support at the other side on which the other 25 flanging heads are mounted. The flanging head includes a sleeve 3, and this sleeve 3 is mounted on the support 2 so that it may move endwise thereon. At the left-hand end of the sleeve there is a roller 4 which ex- 30 tends laterally from the sleeve and engages in a cam groove 5 formed in a stationary cam 6. In Fig. 1, a section is taken through the upper and lower flanging heads, and as they are similar in construction, a de- 35 scription of one will answer for the other, the only difference being that the cam groove has shifted the sleeve in the lower portion of the view so as to move the head proper of the flanging head to its extreme movement to 40 the right. This sleeve carries a head portion 7 which is also provided with a cap or cover part 8. In between this cap and the head 7 is a sectional forming plate 9. This sectional forming plate preferably is made in 45 four sections as shown in Fig. 2, and these sections are so shaped that when they are moved into closed position, they form one continuous piece, in effect, and when moved to open position, they will be slightly spaced 50 from each other. Said sections are moved from open to closed position and vice versa by means of a controlling ring 10, which controlling ring is provided with pins 11 which extend into inclined slots 12 formed in each 55 section of the forming ring. There are four inclined slots and four pins which engage the same. These sectional members of the forming ring are located between the end of cap plate 8 and the head 7 of the flanging 60 head, and are adapted to slide in grooves formed in said head. The ring 10 is located in a recess formed in the flanging head 7. Said ring is provided with an outwardly extending arm 13 carrying a roller 14 adapted 65 to cooperate with the stationary member

whereby said ring is oscillated to a limited extent and moves the segments of the forming ring radially of the flanging head.

Located within the sleeve 2 is a stem 15 on which a die head 16 is mounted. Said die head is larger in diameter than the stem. The stem at its outer end carries a roller 17 which runs in a groove 18 in the stationary member 6, and as the machine rotates, this stem 15 will be moved out and in, that is, relative to the sleeve 2 and also with the sleeve as it reciprocates. The die head 16 has a tapered portion 19 which enters the can body, but does not engage the can body, any more than to center it if it is slightly off center. At the base of the die head there is a cylindrical portion 20 of larger diameter than the can body to be flanged. Between this tapered portion 19 and the cylindrical portion 20 there is a forming die 21 which is of such size relative to the diameter of the can body, that the can body will pass over the die and along the die, said die being curved so as to cause the metal to flow outwardly into the flange. The die head 16 is also provided with a portion 22 which is of slightly less diameter than the portion 21 so as to make proper clearance for the metal. The forming ring 9 is provided with an inner face 23 which is cylindrical and serves 95 as a limiting wall for limiting the flow of the metal by its contact with the die shaping part 21, and thus determine the width of the flange formed in the can body. It will be understood, of course, that these sectional members of the ring are moved to closed position as shown in the lower part of Fig. 1, when the flange is being formed. Each of the sections of the forming ring is provided with a shoulder 24 which projects inwardly from the limiting surface 23. The parts are in the position shown in the lower half of Fig. 1 when the entire flanging head is moved forward through the action of the rolls 4 and 17 running in the cam grooves 100 in the stationary member 6. It is understood, of course, that the other flanging head of the pair moves forward at the same time, and these flanging heads enter the can body indicated in the drawings at B, so that the 105 flanges at the opposite ends of the body are simultaneously formed. The can body does not have to be clamped in any way, as one head operates to prevent endwise movement of the body through the flanging action of the other head. In other words, both flanging heads move together on to the can body. The end of the can body moves in between the forming ring and the die head until its extreme edge comes in contact with the die 110 21, which causes the metal simultaneously throughout the entire extent of the can body, to flow outwardly, and said metal will continue to flow outwardly until it strikes the limiting wall 23. If it should happen that 115 20

the metal at one end of the can body is harder than it is at the other, then one flange might form before the other forms, but as soon as the edge of the metal abuts against the forming ring, then of course, the other end of the can body will have its flange formed. It is noted that when the metal flows out into contact with the limiting ring, it passes in behind the shoulder or abutment 24. The sleeve 10 3 is timed in its movements so as to move to the left as viewed in Fig. 1 after the flange has been turned, and this causes the shoulder to engage the inner or right-hand face of the flange on the end of the can body, while the 15 outer or left-hand face of the flange is in engagement with the vertical wall of the flanging die 21. Both the inner and outer faces of the flange are now subject to a shaping action, which insures that the flange shall 20 stand at a proper angle to the body portion, with the shoulder at the inner edge of the flange, which shoulder joins the flange to the can body, properly shaped, to give the best efficiency in the rolling of the flange 25 into a double seam. It will be noted that the flange is therefore under control during the turning of the flange and the shaping of the flange, and this control is positive, and will always make the flange of the same shape 30 and width, regardless of any varying of the quality or character of the metal forming the can body. By having these flanges made uniform, the can ends which are attached to the body in the attaching of the bottom 35 and the closing of the can body, may be made of the minimum amount of metal without danger of forming a leak in the finished seam.

It will be noted that the inner face of each 40 of the segments of the bumping ring are curved on a circle, the radius of which is the radius of the external curved surface on the can body which is to be flanged. Therefore, when these segments are forced inwardly 45 they will come to a position close up to the can body underneath the flange and this will cause the entire inner face of the flange to be subject to shaping by the bumping ring. After the flange has been turned, the internal 50 or die shaping half of the flanging head is withdrawn slightly before these segments are opened, and therefore, the segments will operate to strip the can body from the opposite inner flanging head or die. After this, 55 the segments are moved to open position so that upon further movement of the flanging head, the outer portion thereof, or the bumping ring, will readily pass over the flange and thus entirely free the can body so that it may 60 be ejected from the machine.

It is obvious that other ways of operating the parts and forming the flange may be utilized than those described specifically above, as the invention is directed broadly to 65 the method of forming a flange which is

under constant control during the entire formation thereof, and which method always results in a uniform formation of flanges, and also to a structure broadly for carrying out said method. 70

Having thus described the invention, what I claim as new and desire to secure by Letters-Patent, is—

1. A flanging head for can bodies including a flange turning die having means for engaging the outer face of the flange when it is formed, means for limiting the width of the flange formed on the can body, means for engaging the inner face of the formed flange, and means for moving said last-named means relative to the flanging head for shaping the flange into a predetermined form. 75

2. A flanging head for can bodies including a flange turning die, means for supporting and moving said flange turning die into the can body to be flanged, said flange turning die having means for engaging the outer face of the formed flange, means for limiting the width of the flange turned on the can body by the movement of the flange turning die, means for engaging the inner face of the flange, and means for moving said last-named means into engagement with the inner face of the flange whereby said flange is forced against the portion of the flange turning die engaging the outer face of the flange for shaping the same into a predetermined form. 85

3. A flanging head for can bodies including a moving support, a sleeve mounted on said support, a stationary cam for moving the sleeve endwise as the support moves, a reciprocating member located within said sleeve, means for reciprocating said member as the support moves, a flange turning die carried by said member, a sectional bumper ring carried by said sleeve, said die operating upon the reciprocation thereof to simultaneously form a flange all the way around the end of the can body, said bumper ring having means for limiting the width of the turned flange, and means cooperating with the flanging head carrying the die for engaging both faces of the flange and shaping the same into a predetermined form. 90

4. A flanging head for can bodies including a moving support, a sleeve mounted on said support, a stationary cam for moving the sleeve endwise as the support moves, a reciprocating member located within said sleeve, means for reciprocating said member as the support moves, a flange turning die carried by said member, a sectional bumper ring carried by said sleeve, said die operating upon the reciprocation thereof to simultaneously form a flange all the way around the end of the can body, said bumper ring having means for limiting the width of the turned flange, means cooperating with the flanging head carrying the die for engaging 105 110 115 120 125 130

- both faces of the flange and shaping the same into a predetermined form, the sections of the bumper ring being curved at their inner faces so as to conform substantially to the 5 curved surface of the can body all the way around when said sections are in closed position underneath the flange, and means for moving the sections of the bumper ring to closed position about the can body and to 10 open position so as to permit said bumper ring to pass over the flange when releasing the can body.
5. A flanging head for can bodies including a moving support, a sleeve mounted on 15 said support, a stationary cam for moving the sleeve endwise as the support moves, a reciprocating member located within said sleeve, means reciprocating said member as the support moves, a flange turning die carried by said member, a sectional bumper ring carried by said sleeve, said die operating upon the reciprocation thereof to simultaneously 20 form a flange all the way around the end of the can body, said bumper ring having means for limiting the width of the turned flange, means cooperating with the flanging head carrying the die for engaging both faces of the flange and shaping the same into a predetermined form, means for moving the sections 25 of the bumper ring to closed position around the can body, and to open position to permit the ring to pass over the flange, said sectional bumper ring being timed so as to remain substantially in closed position, until 30 the can body is stripped from the turning dies, and then moved to open position to pass over the flange.
6. A flanging head for can bodies including a moving support, a sleeve mounted on 35 said support, a stationary cam for moving the sleeve endwise as the support moves, a reciprocating member located within said sleeve, means reciprocating said member as the support moves, a flange turning die carried by said member, a sectional bumper ring carried by said sleeve, said die operating upon the reciprocation thereof to simultaneously 40 form a flange all the way around the end of the can body, said bumper ring having means for limiting the width of the turned flange, means cooperating with the flanging head carrying the die for engaging both faces of the flange and shaping the same into a predetermined form, means for moving the sections 45 of the bumper ring to closed position around the can body, and to open position to permit the ring to pass over the flange, said sectional bumper ring being timed so as to remain substantially in closed position, until 50 the can body is stripped from the turning dies, and then moved to open position to pass over the flange.
- 55 before the turning die completes its movement which turns the flange, so that the flange striking the inner surface of the bumper ring is limited.
7. A flanging head for can bodies including a moving support, a sleeve mounted on 60 said support, a stationary cam for moving the sleeve endwise as the support moves, a reciprocating member located within said sleeve, means reciprocating said member as the support moves, a flange turning die carried by said member, a sectional bumper ring carried by said sleeve, said die operating upon the reciprocation thereof to simultaneously 65 form a flange all the way around the end of the can body, said bumper ring having means for limiting the width of the turned flange, means cooperating with the flanging head carrying the die for engaging both faces of the flange and shaping the same into a predetermined form, means for moving the sections 70 of the bumper ring to closed position around the can body and to open position to permit the ring to pass over the flange, said sectional bumper ring being timed so as to remain substantially in closed position, until 75 the can body is stripped from the turning dies and then moved to open position to pass over the flange, said means for operating the sleeve and the means for operating the member carrying the turning die being timed so that said bumper ring is moved to closed position before the turning die completes its movement which turns the flange, so that the flange striking the inner surface of the bumper ring is limited, and so that said bumper ring is forced against the face of the flange adjacent thereto and caused to force the flange into contact with the wall on the flange turning die whereby said flange 80 is shaped to a predetermined form.
8. A flanging head for can bodies including a moving support, a sleeve mounted on 85 said support, a stationary cam for moving the sleeve endwise as the support moves, a reciprocating member located within said sleeve, means reciprocating said member as the support moves, a flange turning die carried by said member, a sectional bumper ring carried by said sleeve, said die operating upon the reciprocation thereof to simultaneously 90 form a flange all the way around the end of the can body, said bumper ring having means for limiting the width of the turned flange, means cooperating with the flanging head carrying the die for engaging both faces of the flange and shaping the same into a predetermined form, means for moving the sections 95 of the bumper ring to closed position around the can body and to open position to permit the ring to pass over the flange, said sectional bumper ring being timed so as to remain substantially in closed position, until 100 the can body is stripped from the turning dies and then moved to open position to pass over the flange, said means for operating the sleeve and the means for operating the member carrying the turning die being timed so that said bumper ring is moved to closed position before the turning die completes its movement which turns the flange, so that the flange striking the inner surface of the bumper ring is limited, and so that said bumper ring is forced against the face of the flange adjacent thereto and caused to force the flange into contact with the wall on the flange turning die whereby said flange 105 is shaped to a predetermined form.
- 110
- 115
- 120
- 125
- 130

pass over the flange, said means for operating the sleeve and the means for operating the member carrying the turning die being timed so that said bumper ring is moved to 5 closed position before the turning die completes its movement which turns the flange, so that the flange striking the inner surface of the bumper ring is limited, and so that said bumper ring is forced against the face 10 of the flange adjacent thereto and caused to force the flange into contact with the wall on the flange turning die whereby said flange is shaped to a predetermined form, said bumper ring being proportioned and shaped 15 at the inner face thereof so as to engage the flange throughout substantially the entire width thereof and extent thereof.

9. A flanging head for can bodies including a moving support, a sleeve mounted on 20 said support, a stationary cam for moving the sleeve endwise as the support moves, a reciprocating member located within said sleeve, means reciprocating said member as the support moves, a flange turning die carried by said member, a sectional bumper ring 25 carried by said sleeve, said die operating upon the reciprocation thereof to simultaneously form a flange all the way around the end of the can body, said bumper ring having 30 means for limiting the width of the turned flange, means cooperating with the flanging head carrying the die for engaging both faces of the flange and shaping the same into a predetermined form, means for moving the 35 sections of the bumper ring to closed position around the can body and to open position to permit the ring to pass over the flange, said sectional bumper ring being timed so

as to remain substantially in closed position until the can body is stripped from the turning dies and then moved to open position to 40 pass over the flange, said means for operating the sleeve and the means for operating the member carrying the turning die being timed so that said bumper ring is moved to closed 45 position before the turning die completes its movement which turns the flange, so that the flange striking the inner surface of the bumper ring is limited, and so that said 50 bumper ring is forced against the face of the flange adjacent thereto and caused to force the flange into contact with the wall on the flange turning die whereby said flange is shaped to a predetermined form, and means for opening and closing the sections of the 55 bumper ring, said means being timed so as to cause the bumper ring to engage the flange at one end of the can body and strip the other end of the can body from the turning die 60 after which the sections of the bumper ring are moved to open position so as to pass over the flange and allow the can body to be ejected from the machine.

10. The method of forming flanges on a can body comprising forcing a turning die 65 into the open end of a can body for simultaneously turning the metal at the end of the can body outwardly into a flange, engaging the edge of the forming flange for limiting the width of the same, and simultaneously engaging both faces of the flange 70 after it is formed for shaping the same to a predetermined form.

In testimony whereof, I affix my signature.

HENRY A. FINK.
